UNITED STATES PATENT OFFICE

2,081,795

SULPHOAROMATIC COMPOUND OF CERTAIN HIGHER ALIPHATIC KETONES

Melvin De Groote, St. Louis, Mo., assignor to
Tretolite Company, Webster Groves, Mo., a
corporation of MissouriNo Drawing. Application June 8, 1936,
Serial No. 84,180

7 Claims. (Cl. 260—131)

This invention relates to a new composition of matter or chemical compound that is capable of use for various purposes, including use as a fat splitting agent, a wetting agent, a dispersing agent, or a detergent. It is known that certain fatty acids or fatty compounds, characterized by the presence of an ethylene linkage, or by the presence of an alcoholiform hydroxyl, or by both, may be converted into sulphoaromatic fatty acids of the kind known as Twitchell reagents. Suitable fatty acids for the manufacture of Twitchell reagents include erucic acid, oleic acid, etc. Fatty acids containing more than one ethylene linkage, such as linoleic acid or linolenic acid, may be employed. Similarly, hydroxy-stearic acid or dihydroxy-stearic acid may be employed. Ricinoleic acid may be employed. Ricinoleic acid reacts with sulphuric acid at the alcohol hydroxyl in preference to the ethylene linkage. Hydrogenated ricinoleic acid, in which the hydroxyl is intact, may be employed. Acetylated ricinoleic may be used. The various fatty acids or their more available form, such as the glyceride, of the kind specified, are characterized by the fact that they react with sulphuric acid to form acid sulphates.

It is well known that various fatty acids may be treated in various manners to yield ketones. Reference is made to Chemical Technology and Analysis of Oils, Fats, and Waxes, sixth edition (1921), volume 1, pp. 146 and 153. It is to be noted that certain fatty ketones, such as oleone and erucicone, described by Lewkowitsch, are characterized by the presence of an ethylene linkage in each of the two fatty acid residues which enter into the composition of the compound. Such ketones will react with sulphuric acid to form acid sulphates which decompose at least slowly in presence of dilute acid to liberate sulphuric acid. Similar ketones, such as hydroxy-stearone, dihydroxy-stearone, ricinoleone, etc., may be prepared by similar methods. The preparation of the higher ketones is usually conducted in the manner indicated by Lewkowitsch, to-wit, heating the fatty acids with iron filings to about 350° C. In the subsequent description, I shall refer to oleone, because it is the cheapest available higher fatty ketone; but it is to be understood that any of the higher fatty ketones which react with sulphuric acid to form acid sulphates may be employed.

I have found that when one molecular weight of oleone, or a similar material, is mixed with one or two molecular weights of a suitable aromatic compound of the same kind which is customarily

employed in the manufacture of Twitchell reagents, and when said mixture is subjected to sulphonation in a manner employed in the manufacture of Twitchell reagents or in the manner employed in the sulphonation of various fatty acids, or fatty compounds, one obtains a new chemical compound. Such a product is characterized by the fact that one or two sulphoaromatic residues are introduced so as to form addition products or substitution products of the particular higher fatty ketone which is being employed. In the use of oleone, the ethylene linkage disappears with complete saturation by introduction of a hydrogen atom and a sulphoaromatic residue, thus forming an addition product. In the employment of hydroxy-stearone, the sulphoaromatic residue replaces the alcoholic hydroxyl, and thus is a substitution product. In some instances, and especially where it is desirable to obtain light-colored products, I have found that the method employed in producing certain sulphoaromatic compounds, such as sulphoaromatic derivatives of heneicosic acid is desirable. This method involves sulphonation in presence of certain organic acids or their anhydrides and is limited to use with non-hydroxy ketones. Such procedure is described in U. S. Patent 2,030,492, dated April 9, 1936, to De Groote and Keiser.

In the manufacture of Twitchell reagents, the aromatic materials customarily employed are benzene, naphthalene, phenol, cresol, etc. Toluene and xylene are sometimes employed. Beta naphthol is sometimes employed. Tetralin may be employed. Anthracene, hydrogenated anthracene or phenanthrene have been found useful in the manufacture of such sulphoaromatic fatty acids. These aromatic substances employed are characterized by the fact that they produce monosulphonic acids when treated with sulphuric acids of proper strength and under the proper conditions, and are also characterized by the fact that when such sulphonic acids are contacted with higher fatty acid sulphates, such as the acid sulphate derived from oleic acid, that condensation takes place, presumably with the elimination of sulphuric acid. Aromatic compounds of this kind are commonly referred to as being susceptible to Twitchell condensation.

A molecule of oleone may be admixed with one molecule of benzene, or two molecules of benzene, or with one or two molecules of phenol, or with one or two molecules of naphthalene. It is also obvious that two different aromatic materials might be employed; for instance, one molecule

of oleone may be mixed with one molecule of phenol and one molecule of naphthalene. The sulphonation process, of course, is conducted after mixture, but it is also evident that one might convert the aromatic material into a sulphonic acid and convert the selected ketone into a mono-acid sulphate or a di-acid sulphate, prior to admixture with the aromatic material.

It is to be noted that if one has the ketone of an unsaturated hydroxy acid, such as ricinoleone, not only will it be hypothetically possible to introduce a sulphaaromatic residue at each ethylene linkage, but also at each alcoholiform hydroxyl. However, if such materials are formed at all, apparently they are relatively unstable, or else their formation is prevented by some phenomenon such as steric hindrance. If one had available the ketone derived from an unsaturated hydroxy acid in which the separation in the hydrocarbon chain between the alcohol hydroxyl and the ethylene linkage happened to be greater than in the case of ricinoleone, then possibly three or four sulphaaromatic residues could be so introduced.

It is understood, of course, that more than one sulphonic acid residue may be introduced into the aromatic nucleus. For instance, instead of introducing one sulphonic acid residue into a naphthalene nucleus, one might substitute two or even more.

It is possible that subsequently there may become available higher fatty ketones derived from two different fatty acids; for instance, a ketone derived from one molecule of oleic acid and one molecule of stearic acid. It is apparent that as long as one of the fatty residues entering into the composition of the ketone contains an ethylene linkage or an alcoholiform hydroxyl, such a mixture ketone would be satisfactory for producing the type of material herein contemplated.

Oleone, $(C_{17}H_{33})_2CO$, prepared by treatment of oleic acid with iron filings at about $350^{\circ} C.$, is treated with sulphuric acid monohydrate at a relatively low temperature, approximately 10° to $30^{\circ} C.$, until the product is converted into the di-acid sulphate of the composition

Similarly, phenol is converted into phenol sulphonlic acid in the conventional manner. It is unnecessary to separate either the sulphonated aromatic material or the sulphated ketone from the excess acid employed in sulphonation in one instance, and in sulphation in the other instance. The acid masses are mixed in such proportion that 700 pounds of $(C_{17}H_{34} \cdot HSO_4)_2CO$ is mixed with 350 pounds of phenol sulphonlic acid. This calculation is based on the assumption that all the oleone was converted into the hydrogen sulphate and that all the phenol was converted into phenol sulphonlic acid. The above mixture is intended to combine two molecules of phenol sulphonlic acid with one molecule of

After combining the two acid masses, the mixture is stirred cautiously at a temperature of about 30° to $35^{\circ} C.$ and the temperature raised carefully to slightly under $40^{\circ} C.$, if need be, until condensation has taken place and a compound of the following composition formed:

If condensation or combination does not take

place readily enough, it may be desirable to add oleum containing 20% to 25% sulphur trioxide in relatively small amounts, for instance, 5% by weight of the total acid mass. The reaction should go to completion within 10 to 30 hours, and in some instances is substantially complete within four or five hours or even less.

Completion of reaction can be determined in the following manner: A small amount of the acid mass is diluted with three or four volumes of water and boiled under reflux condenser for approximately 30 minutes. It is then poured into a separatory funnel and the lower layer of dilute acid withdrawn. The upper oily layer is then diluted with a large excess of water and should produce a clear solution which indicates that the entire mass is water soluble, due to the formation of the compound $(C_{17}H_{34} \cdot OH \cdot C_6H_3 \cdot HSO_3)_2CO$, and indicates that it is not a mixture of sulphaaromatic material and $(C_{17}H_{33})_2CO$. It is to be noted that any $C_{17}H_{34} \cdot HSO_4CO$ which is uncombined is decomposed by boiling dilute acid and converted into the water insoluble ketone. If the sulphaaromatic derivative is soluble in acid of the dilution used during the boiling process, then in such event, at the end of the boiling period the product gives a clear solution without separation of any upper oily layer. The upper oily layer being water soluble, may, however, be salted out by the acid present during boiling, and therefore the step of separation and subsequent dilution is necessary.

At the completion of the reaction, the acid mass is diluted with approximately twice its volume of cold water and the mixture stirred until homogeneous. The mixture is allowed to separate and the lower layer consisting of dilute acid is withdrawn and discarded, the upper layer representing $(C_{17}H_{34} \cdot OH \cdot C_6H_3 \cdot HSO_3)_2CO$. It is then employed in its acid state or is neutralized in any suitable manner. It may be neutralized with such materials as sodium hydroxide, potassium hydroxide, ammonium hydroxide, or the corresponding carbonates or bicarbonates. It may be neutralized with such materials as calcium or magnesium oxides or hydroxides. It may be neutralized with a suitable amine, such as triethanolamine, butylamine, amylamine, benzylamine, cyclohexylamine, aniline, etc. Some of the products so obtained not only are soluble in water, but are also soluble in hydrophobe vehicles such as gasoline or kerosene. Some compounds may be oil soluble and rather insoluble in water. Salts of the heavy metals, such as iron, copper, and the like, can also be obtained if desirable. It is my preference to convert the material above described into the sodium salt having the composition $(C_{17}H_{34} \cdot OH \cdot C_6H_3NaSO_3)_2CO$.

It is known that pyrolytic decomposition of ricinoleic acid or castor oil causes the molecule to break at the hydroxyl position and yields a sulphonatable unsaturated "fatty" acid having 11 carbon atoms. It is understood that the expression "fatty" is here used because the acid thus obtained in such pyrolysis is a lower homologue of oleic acid. However, so far as I am aware, this acid does not occur naturally in any fat or oil. This particular acid, $C_{11}H_{20}O_2$, of course, can be converted into a corresponding ketone, which can thereafter be converted into sulphaaromatic derivatives of the kind herein described. For practical purposes, then the ketones employed to form the products herein described must be derived from fatty acids of their derivatives capable of forming acid sulphates, and said fatty acids

must come within the molecular weight range indicated by the variation from hendecenoic acid, $C_{11}H_{20}O_2$, to erucic acid, $C_{22}H_{42}O_2$.

The presence of more than one sulphonic acid residue, in one or more of the aromatic nuclei, increases water solubility.

As previously pointed out, an acidic hydrogen atom may be present in the compound as such or it may be neutralized or esterified so that it 10 is replaced by a metallic atom, ammonium radical, amine residue or radical, or by an organic radical such as an alkyl radical or aryl radical. The expression "ionizable hydrogen equivalent" is employed to indicate such acidic hydrogen atom or 15 its equivalent of the kind indicated.

Having thus described my invention, what I claim as new and desire to secure by Letters Patent is:

1. A new chemical compound consisting of sul- 20 phoaromatic derivatives of ketones obtained by sulphonation and condensation reactions involving aromatic compounds of the kind which are susceptible to Twitchell condensation and aliphatic ketones derived from fatty acids having at 25 least 11 carbon atoms and not more than 22 carbon atoms, said ketones being additionally characterized by being susceptible to sulphation.

2. A new chemical compound consisting of sul- 30 phoaromatic derivatives of ketones of the kind indicated by the type formula

35 in which R represents the radical— $R'' \cdot T \cdot SO_3 \cdot Z$ and R' represents the radical— $R''' \cdot T' \cdot SO_3 \cdot Z$ in which R'' and R''' represent residues derived from fatty acids having at least 11 carbon atoms and not more than 22 carbon atoms in the chain and 40 susceptible to sulphation; T and T' represent an aromatic residue derived from an aromatic body susceptible to Twitchell condensation; SO₃ is the conventional sulphonic acid residue; and Z is an ionizable hydrogen atom equivalent.

45 3. A new chemical compound consisting of sul- phoaromatic derivatives of ketones of the kind indicated by the type formula

50 in which R represents the radical— $R'' \cdot T \cdot SO_3 \cdot Z$ and R' represents the radical— $R''' \cdot T' \cdot SO_3 \cdot Z$, in which R'' represents a residue derived from a fatty acid having at least 11 carbon atoms and 55 not more than 22 carbon atoms in the chain and susceptible to sulphation; T and T' represent an aromatic residue derived from an aromatic

body susceptible to Twitchell condensation; SO₃ is the conventional sulphonic acid residue; and Z is an ionizable hydrogen atom equivalent; both fatty acid residues indicated by R'' being identical.

4. A new chemical compound consisting of sul- phoaromatic derivatives of ketones of the kind indicated by the type formula

in which R represents the radical— $R' \cdot T \cdot SO_3 \cdot Z$, in which R' represents a residue derived from a fatty acid having at least 11 carbon atoms and not more than 22 carbon atoms in the chain and susceptible to sulphation; T represents an aromatic residue susceptible to Twitchell condensation; SO₃ is the conventional sulphonic acid residue; and Z is an ionizable hydrogen atom equivalent; both fatty acid residues indicated by R' being identical and both aromatic residues indicated by T being identical.

5. A new chemical compound consisting of sul- phoaromatic derivatives of ketones of the kind indicated by the type formula

30 in which R represents the radical— $R' \cdot T \cdot SO_3 \cdot Z$, in which R' represents a residue derived from a fatty acid having at least 11 carbon atoms and not more than 22 carbon atoms in the chain and susceptible to sulphation; T represents a mono- 35 cyclic aromatic residue susceptible to Twitchell condensation; SO₃ is the conventional sulphonic acid residue; and Z is an ionizable hydrogen atom equivalent.

6. A new chemical compound consisting of sul- phoaromatic derivatives of ketones of the kind indicated by the type formula

40 in which R represents the radical— $R' \cdot T \cdot SO_3 \cdot Z$, in which R' represents a residue derived from a fatty acid having at least 11 carbon atoms and not more than 22 carbon atoms in the chain and susceptible to sulphation; T represents a phenol residue; SO₃ is the conventional sulphonate acid residue; and Z is an ionizable hydrogen atom equivalent.

7. A new chemical compound indicated by the formula $(C_{17}H_{34} \cdot OH \cdot C_6H_5 \cdot NaSO_3)_2CO$.

MELVIN DE GROOTE.

Certificate of Correction

Patent No. 2,081,795.

May 25, 1937.

MELVIN DE GROOTE

It is hereby certified that errors appear in the printed specification of the above numbered patent requiring correction as follows: Page 2, first column, lines 48 and 66, and second column, line 21, for the formula " $C_{17}H_{34} \cdot HSO_4 \cdot CO$ " read $(C_{17}H_{34} \cdot HSO_4)_2CO$; and that the said Letters Patent should be read with these corrections therein that the same may conform to the record of the case in the Patent Office.

Signed and sealed this 20th day of July, A. D. 1937.

[SEAL]

HENRY VAN ARSDALE,
Acting Commissioner of Patents.
